RESILIENT CONNECTOR FOR DISPLAY PARTITIONS OR THE LIKE

David M. Moore, Pittsburgh, Pa., assignor to Armstrong
Store Fixture Corporation, Pittsburgh, Pa.

Filed Sept. 1, 1972, Ser. No. 285,827

Term of patent 14 years

Int. Cl. D8—08

U.S. Cl. D8—259

FIG. 1.

FIG. 2.

FIG. 1 is a perspective view of a resilient connector for display partitions or the like, the broken lines of a partition being for illustrative purposes only.

FIG. 2 is a perspective view of the connector of the present invention.

I claim:

The ornamental design for a resilient connector for display partitions or the like, as shown and described.
